Primary Examiner—Philip S. Hyder*Attorney, Agent, or Firm*—Ladas & Parry[57] **CLAIM**

The ornamental design for a pistol case, as shown and described.

DESCRIPTION

FIG. 1 is a top, front and right side exploded perspective view of a pistol case showing my new design;

FIG. 2 is a top, front and right perspective view of the pistol case of FIG. 1 in an assembled state;

FIG. 3 is a front elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a rear elevational view thereof;

FIG. 9 is a perspective view of the front of one of the inserts shown in FIG. 1;

FIG. 10 is a perspective view of the back of the insert shown in FIG. 9;

FIG. 11 is a perspective view of the front of another insert shown in FIG. 1;

FIG. 12 is a perspective view of the back of the insert of FIG. 11; and,

FIG. 13 is a perspective view from the bottom of a removable case shown in the exploded perspective view of FIG. 1.
